UNITED STATES PATENT OFFICE.

CHRISTIAN GILSON, OF WILKINSBURG, PENNSYLVANIA, ASSIGNOR TO WESTINGHOUSE ELECTRIC & MANUFACTURING COMPANY, A CORPORATION OF PENNSYLVANIA.

BLADE.

1,286,284.

Specification of Letters Patent.

Patented Dec. 3, 1918.

Original application filed December 30, 1914, Serial No. 879,754. Divided and this application filed February 27, 1917. Serial No. 151,349.

To all whom it may concern:

Be it known that I, CHRISTIAN GILSON, a citizen of the United States, and a resident of Wilkinsburg, in the county of Allegheny 5 and State of Pennsylvania, have made a new and useful Invention in Blades, (which is a division of application serially numbered 879,754, filed December 30, 1914,) of which the following is a specification.

10 This invention relates to blades and has for an object to produce a blade having a new and improved shrouding member formed thereon.

15 A further object is to produce a blade having a combined spacing and shrouding member and a shroud engaging tip formed integrally therewith.

20 A further object is to produce a blade which is provided with a shrouding member formed from a part of the outer end of the blade.

25 These and other objects, which will be made apparent throughout the further description of my invention, are attained by means of the blade herein described and illustrated in the single sheet of drawings accompanying and forming a part hereof.

30 In the drawings Figures 1, 2, 3 and 4 are perspective views of a blade in various stages of completion, the finished blade being shown in Fig. 1.

Fig. 5 is a perspective view of several completed blades assembled in a row.

35 Fig. 6 is a fragmental sectional view of the rotor element of a turbine or similar apparatus equipped with blades embodying my invention.

40 The blade illustrated is provided with a mounting portion such as a shank 5, a central portion or blade proper 6, a shrouding member 7, and a shroud engaging tip 8 formed on the outer end of the blade proper. This blade is preferably formed as shown in the first four figures, the original blank being 45 made by either forging, drawing, or casting. As shown in Fig. 1, the wings of the outer ends of the blade are first severed and bent flat. The flattened portion is then milled so as to form the shrouding member 50 7 and the shroud engaging tip 8. The shrouding member 7 is then bent over and punched as shown so as to form a recess 9 for engaging the rear part of the shrouding member of an adjacent blade, as shown in

Fig. 5, and a tongue 10 for engaging the recess of the adjacent shrouding member on the opposite side of the blade. A hole 11 is also punched in the shrouding member 7, into which the shroud engaging tip 8 of the adjacent blade fits. 60

Fig. 5 illustrates the manner in which the blades fit together. Because of the interlocking of the tongues 10 in the recesses 9 and the tips 8 in the holes 11 the blades may be accurately and quickly assembled in 65 proper alinement. The tips 8 are then riveted over thereby locking the blades together and preventing vibrations of the blades during operation. It is evident that both the tongues 10 and the shroud engaging tips 8 70 coöperate to prevent either lateral or circumferential vibrations.

In Fig. 6, I have illustrated blades having inclined shrouding members for the purpose of providing fluid passages of gradually increasing area through the blades. 75 These blades are preferably formed by severing the blanks at an angle instead of at right angles, as shown in Fig. 1. The parts of these blades which correspond to similar parts of the blade shown in Fig. 4 are designated by similar numerals distinguished by prime marks.

80 While I have described and illustrated several embodiments of my invention, it will 85 be apparent to those skilled in the art that various changes, modifications, additions and omissions may be made in the apparatus illustrated without departing from the spirit and scope of the invention as set forth 90 by the appended claims.

What I claim is:

1. A blade formed of malleable material and having an integrally formed shroud member on the outer end thereof, said shroud 95 member being flat and being pressed to a position substantially at right angles to the axis of the blade.

2. A blade having an integrally formed malleable shrouding member at one end 100 thereof pressed into engagement with the adjacent ends of the wings of the blades.

3. A blade having a shrouding member formed of malleable material and located on the outer end thereof, said shrouding member being provided with a recess and tongue for causing adjacent blades to interlock and form a continuous shroud, and being pressed 105

to a position substantially at right angles to the blade.

4. A blade having a shroud engaging tip and a shrouding member integrally formed on the outer end of the blade, said shrouding member having a hole therein for engaging the shroud engaging tip of an adjacent blade.

5. A blade having a shroud engaging tip and a shrouding member integrally formed

on the outer end of the blade, said shrouding member having a hole therein for engaging the shroud engaging tip of an adjacent blade and a tongue and recess for causing adjacent shrouding members to interlock.

In testimony whereof, I have hereunto 15
subscribed my name this 26th day of February, 1917.

CHRISTIAN GILSON.
